SAFETY RAZOR

John Holtzman, New York, N. Y., assignor to
American Safety Razor Corporation, New York,
N. Y., a corporation of Virginia

Original application June 13, 1925, Serial No.
36,802. Divided and this application November
10, 1927, Serial No. 232,218. Renewed January
13, 1932

3 Claims. (Cl. 30—12)

My present invention relates generally to safety razors, and has particular reference to a razor holder for employment with blades of the wafer type.

5 This application constitutes a division of my co-pending application No. 36,802, filed June 13, 1925.

10 The device to which my invention relates comprises in its essence a razor holder which embodies a handle, a blade seat, and a suitable cover for the blade, the seat being provided with a guard edge.

15 It is well known to be of extreme importance from the standpoint of efficient operation that a blade applied to the seat be accurately positioned in a predetermined manner with respect to the guard edge. It is one object of the present invention to provide an arrangement for permitting an adjustment of the blade with respect to the 20 guard edge.

25 More particularly, it is an object of my invention to provide such an arrangement in combination with a guard edge which is provided with blade stops or abutments which define the proper predetermined positional relationship which a blade must assume in order to be most efficiently operative.

30 It is another object of my invention to provide a device wherein means permit a preliminary locating and partial securing of the blade upon a seat. This facilitates usage of the device by obviating any possibility of having the blade slip from the fingers of a user or drop to the floor prior to its final permanent positioning in association with the holder.

35 One feature of my invention lies in providing means for locating and adjusting a blade upon the seat, said means including a member which cooperates with a midportion of the blade. More 40 particularly, it is a feature to provide a member, such as a pin, which extends right through the blade, as for example, through a suitably prepared aperture in the blade.

45 In one form of my invention, the member referred to is adjustable and cooperates with a midportion of the blade for adjusting the latter with respect to the guard edge. I also prefer to provide a spring element for engaging with the rear portion of the blade for advancing the latter 50 against the blade stops and thereby properly locating the cutting edge with respect to the guard edge. Although this form is particularly adaptable for use with single-edged blades having a non-cutting and usually reinforced rear edge, nevertheless it will be obvious that the spring ele-

ment referred to serves a coordinate function from a blade-centering standpoint. Accordingly, although I have herein described and illustrated a device adapted for use primarily with a single-edged blade, nevertheless it will be understood that where a double-edged blade is employed, the adjustable member cooperating with the midportion of the blade may be made to partake of a greater portion of the blade-adjusting, i. e., blade-advancing function.

10 In either event, i. e., regardless of the usage with single or double-edged blades, the member which engages and cooperates with the blade medially thereof serves to partially secure the blade to the seat so as to locate it thereon in approximate position.

15 For the attainment of the foregoing objects and such other objects as may hereinafter appear or be pointed out, I have illustrated one embodiment of my invention in the accompanying drawing, 20 in which—

25 Fig. 1 is a longitudinal cross-section of a holder embodying the features of my invention and showing a typical single-edged blade in association therewith;

Fig. 2 is a plan view of the same device, with the cover thrown back and the blade being indicated only in dot and dash lines; and

Fig. 3 is a view of the blade shown in Figures 1 and 2.

30 I have shown a tubular handle 10 provided at its upper end with a blade seat 11 having a forward guard edge 12 of the usual construction. A cover 13 is hinged to the blade seat 11 at the pivot points 14 arranged on opposite sides of the guard edge 12. The cover 13 is adapted to swing from the position of Figure 2, wherein the blade seat is accessible and uncovered, to the position of Figure 1, wherein the blade seat is covered and the blade thereby enclosed. For the purpose of having the cover snap into closed position and be retained in such position, I provide a spring catch 15 or its equivalent along the free longitudinal edge of the cover 13.

35 In the embodiment illustrated, the cover is 45 hinged so as to swing forwardly over the guard 12 when it is opened; but it will be obvious that my invention is not limited to a construction of this character, it being perfectly satisfactory to associate the cover in any other suitable manner 50 with the blade seat 11.

On opposite sides of the guard edge 12 I provide the blade stops or abutments 16 which define the proper predetermined positional relationship of the cutting edge of the blade with re- 55

spect to the guard edge 12. It will be readily understood that a blade applied to the seat 11 will be in proper position for use when its forward or cutting edge abuts against these stops

5 16.

A bar or rod 17 is rotatably mounted in the handle 10, longitudinal movement thereof being prevented by a set screw 18 or the like which engages a circumferential groove 19 in the rod 10 17. The latter is provided with a knurled knob 20 or the like suitably shaped and positioned to be accessible to the user and manipulable thereby without being objectionably in the way.

The upper portion of the rod 17 is positioned 15 in a suitable bore extending through the seat portion 11; and the extreme portion 21 of the rod 17 is of reduced cross-section and is eccentrically arranged as shown most clearly in Figure 2. The portion 21 projects upwardly through the seat 11.

20 In Figure 3 I have illustrated a blade which is typical of those most suitable for employment with the holder illustrated. Although I have shown a blade having a U-shaped reinforcing portion 22 and a single cutting edge 23 arranged along 25 the opposite longitudinal edge, nevertheless it will be understood that a double-edged blade may be employed with my type of holder with equal facility. The blade shown is provided with an aperture 24 through a medial portion thereof, the 30 aperture shown being elongated in the nature of a slot.

A spring 25, in association with the rear edge 35 of the cover 13, is designed to bear against spaced portions of the reinforcement 22 so as to assure proper centering and advancement of the blade upon the seat and with respect to the guard edge 12.

When the device is used, the blade such as 40 that shown in Figure 3 is applied to the seat 11 so that the pin 21 will project upwardly through the slot or aperture 24. This will serve to initially or preliminarily secure the blade to the seat in a temporary manner and in approximately correct position. Thereupon, the cover 13 is 45 closed, and the spring 25, as well as manipulation of the handle 20, will position the blade forwardly and properly against the stops 16.

It will be obvious that changes in the details herein described and illustrated for the purpose 50 of explaining the nature of my invention may be made by those skilled in the art without departing

from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. A safety razor comprising a blade seat provided with a guard edge and front stops, a cover 10 clamping member pivoted thereto for clamping the blade upon the seat, means carried by the cover clamping member for automatically advancing the blade to bring the shaving edge against the front stops as the cover is brought into blade 15 clamping relation and shiftable means for limiting the advancement of the blade so as to maintain the shaving edge at any predetermined position away from the front stops.

2. A safety razor comprising a blade seat provided with a guard edge and front stops, a cover 20 clamping member pivoted thereto for clamping the blade upon the seat, spring means carried by the cover clamping member for automatically advancing the blade to bring the shaving edge against the front stops as the cover is brought into 25 blade clamping relation and movable means which may be adjusted to limit the advancement of the blade by the spring means and maintain the shaving edge at any predetermined position away from the front stops.

3. A razor assembly comprising a blade seat with cut-away portions to provide an opening therethrough, and with a medial opening, a guard edge on said seat, blade stops at opposite ends of said guard edge, a cover pivoted to said seat, a 35 spring carried by the inside of said cover, a hollow handle, a rotatable rod extending upwardly through the handle and through the opening in said blade seat, said rod having an attenuated eccentric upper end; and a single-edged blade 40 having a slot in its midportion but otherwise unperforated, said blade being adapted to be applied to said seat with said slot engaged over said attenuated upper end of said rod; whereby rotation of said rod about its axis will adjust said blade 45 toward and away from said blade stops, and whereby closing of the cover will cause said spring to bear against the rear edge of said blade to hold the latter forwardly against said stops.

JOHN HOLTZMAN.
